UNITED STATES PATENT OFFICE.

FREDERIC LIONEL GRAHAM, OF NAREEN, VICTORIA.

NIB-EJECTING PENHOLDER.

SPECIFICATION forming part of Letters Patent No. 661,910, dated November 13, 1900.

Application filed September 27, 1900. Serial No. 31,294. (No model.)

To all whom it may concern:

Be it known that I, FREDERIC LIONEL GRAHAM, a subject of the Queen of Great Britain and Ireland, residing at Nareen, in the Colony of Victoria, Australia, have invented certain new and useful Improvements in Nib-Ejecting Penholders; and I do hereby declare the following to be a full, clear, and exact description of the invention, such as will enable others skilled in the art to which it appertains to make and use the same.

The object of this invention is to provide improvements in penholders of that class wherein the nib is ejected by the operation of a part permanently attached to the penholder.

In carrying out my invention I avoid faults which would militate against its extensive adoption. I avoid making it heavy, costly, clumsy, or liable to get out of order. The upper end of the penholder is capable of use as a paper-knife.

To these ends, first, I make each member of my penholder of simple and durable construction; second, the casing of the penholder is not necessarily larger than in ordinary penholders and is of wood, vulcanite, or other material; third, the number of distinct parts in my penholder is four, and, fourth, the assembling of these four parts can be performed rapidly without special tools or skilled labor.

I illustrate my invention by which the above advantages are secured in the accompanying drawings, in which—

Figure 1 shows my penholder in longitudinal section in the position assumed when the spiral spring, hereinafter referred to, has been strongly compressed and has ejected the nib. In the normal position of the parts in Fig. 2 the said spring is compressed slightly. Fig. 2 shows in longitudinal section the parts assembled in normal position with nib inserted; Fig. 3, the plunger with its spiral spring; Fig. 4, a perspective view of a part to be permanently fixed within the casing; Fig. 5, a longitudinal section of the casing, and Fig. 6 a cross-section on the line x to y in Fig. 1. The plunger upper end in Fig. 1 is modified in Figs. 2 and 3. Fig. 1 exhibits the preferred casing, which keeps the plunger from turning, prevents it being pushed objectionably far when ejecting the nib, and enables

its upper projecting end to be wider and stronger than otherwise would be possible.

The hollow casing of my penholder is marked a , its bore or central aperture b being either cylindrical or tapering and smooth throughout, except for an enlargement c near the nib end, and at the other end a slit d on one (preferably the upper) side, as in Figs. 1 and 6.

The plunger has certain features integral in the same piece of metal, as next described. Sheet-metal blanks are stamped out and the lower end (in dotted lines in Fig. 3) is curled up, as shown by firm lines, and slotted in any usual manner to form a nib-holding part e in size such as when slightly compressed to fit in lower end of casing a and when further compressed to allow of a nib being inserted and held tight in the casing, as seen in Fig. 2. Then (in order) there is on the plunger a rib f , against which the back end of the nib is to abut, then a narrow spindle g , then a cylindrical or tapering curled-up portion h , adapted to fit closely against the inner walls of the upper end of the casing, and then a flat (preferably) metal end l of the plunger, this end being normally exterior to the casing and preferably tapering.

k is a spiral spring slipped loosely over the spindle g . The upper end of the spring k abuts on the inner extremity of the upper curled portion h of the plunger, and the lower end of the spring k abuts against the arc or split ring i , which is slipped over the plunger into such position that the inner extremity of the rib f shall abut against it. Each of the ends of this split ring acts as a stop. It may be called a "double-abutment ring," as the edges at each end are turned in as marked j , and it is springy—that is, can be compressed or expanded, resuming when free its normal diameter. The plunger, with spring k extending the full length of spindle g , will pass easily into place in the casing a , but the ring i has to be compressed, so that it may do so. Ring i and spring k being put in place on the plunger the whole are pushed into casing a , the ring i being sprung into the enlargement c from its compressed condition and fitting the same tightly, the shoulders or edges j of the ring nevertheless projecting into the bore b , so that the spring k and the rib f shall abut against the said edges

j at opposite ends of ring *i*. The nib is ejected by pressing forward the plunger, which is retracted by the reaction of the spring *k* from its compressed condition. With a shoulder *m* on the upper side of the plunger and a slit, as *d*, on the upper side of the end of the casing a wider, longer, and better paper-cutter or blade *l* is in that case provided than otherwise, and the shoulder *m* is stopped by the slit end when the part *e* is sufficiently protruded, such stoppage being an advantage.

The above construction is that in which my invention is best embodied; but minor details may be modified without departing from the spirit of my improvements.

What I claim as my invention, and desire to secure by Letters Patent of the United States, is—

1. In a nib-ejecting penholder, the combination with the hollow casing having near the nib end an enlargement of its bore, and having a double-abutment spring-ring sprung thereinto, and a slit in its other end, of a spring-retracted plunger having integrally, in the order stated, the curled-up portion *e*, rib *f*, narrow spindle *g*, curled-up portion *h*, a shoulder *m* and a paper-cutter end *l*, all substantially as and for the purposes set forth.

2. In a nib-ejecting penholder the combination with the hollow casing having near the

nib end an enlargement of its bore and having sprung thereinto a split ring *i* having at each end turned-in edges *j* to serve as abutments, of a plunger having integrally in the order stated, the curled-up portion *e*, rib *f*, narrow spindle *g*, a spiral spring *k* extending the full length of the spindle and bearing against an abutment of ring *i*, curled-up portion *h*, and the projecting paper-cutter or blade *l* all substantially as and for the purposes set forth.

3. In a nib-ejecting penholder, the combination with the hollow casing having near the nib end an enlargement of its bore, and having sprung thereinto a split ring *i* having at each end turned-in edges *j* to serve as abutments, of a plunger having integrally in the order stated the curled-up nib-holding portion *e*, the rib *f*, narrow spindle *g* inclosed by a spiral spring, a curled-up portion *h* fitting within the bore of the casing, and an extremity projecting from the end of the casing, all substantially as and for the purposes set forth.

In testimony whereof I affix my signature in presence of two witnesses.

FREDERIC LIONEL GRAHAM.
